LOOM HAVING AN AUTOMATIC CHANGE
OF THE WEFT COPS

Kurt Schwabe, Le Locle, Switzerland

Application February 20, 1951, Serial No. 211,821
In Switzerland February 20, 1950

12 Claims. (Cl. 139—233)

1

The present invention relates to a control device for looms having an automatic change of the weft cops with the use of electric control means, in which at least one control circuit is provided which bridges over an interrupter lying in the circuit of the electric feeler and selector device of the loom preparing the exchange of the weft cop to be exchanged which interrupts the circuit of the feeler and selector device, when the shuttle with the weft cop to be exchanged has run into the shuttle box wherein the exchange of the weft cop is to be effected, in which control circuit switching members are provided which are operated by control members, which survey the conformity of the kind of the new weft cop put into readiness with the kind of the weft cop to be exchanged in the shuttle, the correct position of the shuttle in the shuttle box, and the correct position of the new weft cop held in readiness, and which bring their holding members into closing position only when these conditions which are indispensable for the faultless exchange of the weft cop are fulfilled, so that by non-compliance with one of these conditions the circuit remains interrupted, which has the consequence that the cop exchange prepared does not take place.

In order that the invention may be better understood and readily carried into effect some embodiments thereof will now be described by way of example with reference to the accompanying drawings, in which:

Fig. 1 shows a diagrammatic general arrangement of one embodiment;

Fig. 2 shows a diagrammatic general arrangement of another embodiment;

Figs. 3 and 4 show details of a third embodiment in elevation.

The embodiments illustrated relate to looms of a kind in which the weft cop is tested by a feeler on the one side of the loom, and is exchanged on the other side in the extreme forward position of the slay. Moreover they are assumed to be looms with one-sided exchange of shuttles in which the shuttle has to pass through a shed twice in succession. The present invention can, however, if appropriately developed, be applied to looms with double-sided independent exchange of shuttles as well as to those in which the exchange of cops is effected in another position of the slay, e. g. in the lowest position of the slay. An illustration of such embodiments of the invention has been dispensed with, since the invention remains substantially the same, and nothing new for the understanding of the invention would emerge therefrom.

In the embodiment according to Fig. 1 the in-

vention is illustrated in connection with an electric colour selector and weft surveying device with which it cooperates. The electric colour selector and weft surveying device per se is not part of the present invention, and in its place could, appropriately fitted-in, a colour selector and weft surveying device of any other design be used at will. For the better understanding, however, the colour selector and weft surveying device illustrated and its operation will be briefly described too.

In Fig. 1 the reference 1 denotes the slay of the loom, 2 the shuttle, in which the empty weft cop 3 to be exchanged is contained, and 4 a pusher member fixed to the slay, which latter cooperates with a two-armed hammer lever 5, when a weft cop is to be exchanged. This hammer lever 5 is articulated by means of a pin 8 to one leg of a two-armed frog 6 which is tiltably pivoted on a pin 7 arranged stationarily in the frame of the loom. On an axle 9 arranged stationarily in the frame of the loom a two-armed control lever 10 is pivoted for rotation, one arm of which acts on one leg of the hammer lever 5, and the other arm of which is acted upon by a relay 11.

The feeler device which is arranged for example on the left hand side of the loom, is constructed according to Fig. 1 as described herein-after:

30 On the shuttle box 12 a series of brushes 13 is provided which bear resiliently against contact plates 14 arranged on the shuttles 2 which brushes are in electrically conductive connection with the clamp 15 for the weft cop 3 in the shuttle 2 and accordingly with the clamp rings 16 of the weft cop 3 and with a metal sleeve 17 arranged on the latter. The shuttle 2 is provided with a weft cop feeler 18 which during the presence of the shuttle 2 in the shuttle box 12 bears against a metal plate 19 which is electrically insulated from and attached to the shuttle box 12 and which establishes an electrical connection of the metal plate 19 to the earth via the metal sleeve 17, the contact plate 14 and the brush 13 when the weft cop 3 has been exhausted. For each cell of the shuttle box 12 such a metal plate 19 is provided, each of which is in electrically conductive connection with a slide rail 20. On the box guide a brush 21 is provided which contacts the slide rail 20 which is associated with that cell of the shuttle box 12 which is on the level of the slay beam, and which is in electrically conductive connection with one terminal of the relay 11 the other terminal of which is connected to the conductor R of a mains R. S. T. 55 The relay 11 is provided with a holding contact 11'.

With 22 the cop magazine is denoted which is rotatably journaled on an axle 23 on the frame of the loom, and which comprises two compartments 22a and 22b which are separated by a partition wall 22' and which are intended for receiving weft cops 3 of two different colours. On the circumference of the cop magazine 22 a cam 24 is arranged which can move between two abutments 25a and 25b, stationarily arranged on the frame of the loom and provided with adjustment screws. By these abutments 25a and 25b the possible rotational movement of the cop magazine 22 on the axle 23 is limited, and a spring acts on the cop magazine 22 in such a sense, that the cam 24 of the latter is pressed against the abutment 25a. In accordance with the weft cops 3 of the two colours there are also two groups of shuttles 2, the shuttles 2 of one group being provided with metal plates 27 in electrically conductive connection with the weft cop feeler 18, whereas with the other shuttles 2 these metal plates are missing. On the shuttle box 12 a resilient brush 28 is arranged, electrically insulated, for each cell of the shuttle box which can contact the metal plate 27 of a shuttle 2 which has run into this cell of the shuttle box. These brushes 28 are each in electrically conductive connection with one slide rail 29. With these slide rails 29 a brush 30 cooperates which is in electrically conductive connection with one terminal of a relay 31, the other terminal of which is connected to the conductor R of the mains R. S. T.

For moving the cop magazine 22 against the action of the spring 26 an electric motor 32, connected to the mains R. S. T., is provided the shaft of which carries a gear pinion 33 which is in mesh with a toothed segment 34 arranged on the cop magazine 22. In the circuit of the electric motor 32 there is arranged a bi-polar switch 35 operated by the relay 31 which is provided with a holding contact 31'.

The control device forming a first embodiment of the present invention, which is arranged on the shuttle box (not illustrated in the drawing) on that side of the loom where the exchange of cops takes place, comprises three resilient contact pins 36, 37a and 37b. The contact pin 36 is in electrically conductive connection with the earth. The contact pins 37a and 37b are each connected with a contact spring 38a and 38b respectively, which cooperate with contact pieces 39a and 39b, respectively, which are connected to the conductor T of the mains R. S. T. Between the contact springs 38a and 38b lies a control cam 40 of electrically insulating material which is arranged on the cop magazine. The arrangement is made in such a manner that in one end position of the cop magazine 22, i. e. when the cam 24 abuts on the abutment 25a, the control cam 40 presses the contact spring 38a against the contact piece 39a, and in the other end position of the cop magazine 22, i. e. when the cam 24 abuts against the abutment 25b, it presses the contact spring 38b against the contact piece 39b. With the contact pins 36, 37a and 37b cooperate two small metal plates which are arranged on each shuttle and which are in electrically conductive connection with one another; to wit, those shuttles 2, which have a metal plate 27, are provided with small metal plates 41 and 42a, and those which have no metal plate 27, are provided with small metal plates 41 and 42b, the distance of the small metal plate 42a from the small metal plate 41 corresponding to the distance of the axes of the contact pins 36 and 37a, and the distance of the small metal plate

42b from the small metal plate 41 corresponding to the distance of the axes of the contact pins 36 and 37b.

With 43 the drum of an interruptor is denoted which consists of electrically insulating material and carries on its circumference a contact strip 44, the said drum being arranged on a shaft which rotates at the same R. P. M. as the crankshaft of the loom. On the periphery of this drum 43 bear two contact springs 45a and 45b, one of which, 45a, is in electrically conductive connection with the earth, and the other, 45b, with the conductor T of the mains R. S. T.

When a shuttle 2 with an exhausted weft cop 3, which is to be exchanged, runs into the shuttle box 12, the following circuit is closed, since the interruptor is so adjusted that at this moment its contact springs 45a and 45b bear on the contact strip 44 of its drum 43:

15 Earth—contact spring 45a—contact strip 44—contact spring 45b—conductor T—conductor R—relay 31—brush 28—slide rail 29—metal plate 19—weft cop feeler 18—metal sleeve 17—contact plate 14—brush 13—earth.

20 When the shuttle 2 with an exhausted weft cop 3, which is to be exchanged, runs into the shuttle box 12, the following circuit is closed, since the interruptor is so adjusted that at this moment its contact springs 45a and 45b bear on the contact strip 44 of its drum 43:

25 Thereby the relay 31 is energized and responds, whereby it rocks the control lever 10 so that the latter moves the hammer lever 5 into such a position that one leg thereof gets into the path of the pusher member 4 of the slay 1. Owing to the 30 holding contact 31' the relay 31 remains energized when the shuttle 2 leaves the shuttle box 12.

When the shuttle 2 containing the weft cop 3 to be exchanged has a metal plate 27, moreover the following circuit is closed:

35 Earth—brush 13—contact plate 14—metal sleeve 17—weft cop feeler 18—metal plate 27—brush 28—slide rail 29—brush 30—relay 31—conductor R, which has the effect that the relay 31 is energized and closes the switch 35. Thereby the electric motor 32 is switched on, and the latter turns now the cop magazine 22 via the gear pinion 33 and the toothed segment 34. This cop magazine 22, which hitherto under the action of the spring 26 had been in a position in which the cam 24 bore on the abutment 25a so that the pusher end of the frog 6 lay above the weft cop to be pushed-in of the compartment 22a of the cop magazine 22, which abutted on the partition wall 22', is thereby turned into its other end position, in which the cam 24 bears on the abutment 25b, so that the pusher end of the frog 6 now lies above the weft cop to be pushed-in of the compartment 22b of the cop magazine 22, which abuts on the partition wall 22'. Owing to the holding contact 31' of the relay 31 the latter remains energized even when the shuttle 2 leaves the shuttle box 12, and the switch 35 accordingly remains closed. When the shuttle 2 containing the weft cop 3 to be exchanged has no metal plate 27, the relay 31 does not respond, the switch 35 is not closed, and accordingly the cop magazine 22 remains in its position.

When the shuttle 2, the weft cop 3 of which is to be exchanged, has run into the shuttle box on the side of the loom opposite to the one where the exchange of the weft cop is to take place, the control device described comes into action. This control device has the object of preventing the exchange of the weft cop initiated by the weft surveying device, when the cop magazine 22 is not adjusted in accordance with the shuttle 2 which has run into the shuttle box, so that consequently a weft cop 3 from the magazine 22 which does not correspond to the colour

of the weft cop 3 to be exchanged would be pushed into the shuttle 2, or when the shuttle 2 with the weft cop 3 to be exchanged does not lie in such a position in the shuttle box, where a safe pushing-in of the new weft cop is safeguarded. This is achieved in the following manner:

When the shuttle 2 with the weft cop 3 to be exchanged passes through the shed, the relay 11 is kept energized by the interruptor, and the hammer lever 5 is kept in readiness. When the shuttle 2 has run into the shuttle box on the other side of the loom, the drum 43 of the interruptor has turned so far that the two contact springs 45a and 45b leave the contact strip 44. Thereby the circuit of the relay 11 would be interrupted, but, immediately before, an electrical connection between conductor T and earth has been effected when the group of the shuttle 2 being under the cop magazine 22 conforms with the group of the weft cop 3 under the frog 6, by one of the two following circuits:

Earth—contact pin 36—small metal plate 41—small metal plate 42a—contact pin 37a—contact spring 38a—contact piece 39a—conductor T, or

Earth—contact pin 36—small metal plate 41—small metal plate 42b—contact pin 37b—contact spring 38b—contact piece 39b—conductor T.

When the group of the shuttle 2 with the weft cop 3 to be exchanged does not conform with the group of the weft cop lying under the frog 6, this bridging does not take place, and the relay 11 is disengaged and returns into its initial position which has the effect that the hammer lever 5 is rocked into a position in which its leg that cooperates with the pusher member 4 of the slay 1 lies outside the path of this pusher member 4 so that the pushing-in of a new weft cop 3 into the shuttle 2 does not take place.

This bridging of the interrupter is not effected either, when the shuttle 2 does not lie in the correct position in the shuttle box, since in this case the contact pins 36 and 37a or 37b, respectively, do not come into contact with the small metal plates 41 and 42a or 42b, respectively. By appropriate choice of the width of the contact areas of the contact pins 36, 37a and 37b on the one hand, and of the small metal plates 41, 42a and 42b on the other hand one has the possibility of adjusting limits for the position of the shuttle 2 in the shuttle box within which the exchange of the weft cop 3 is to be effected.

The embodiment of the invention diagrammatically illustrated in Fig. 2 relates to a control device for a loom which operates with weft cops 50a, 50b, 50c and 50d in four different colours, and for this purpose the loom is provided with a cop magazine 51 which has four compartments 51a, 51b, 51c and 51d. The compartment 51a contains weft cops 50a of the first colour, the compartment 51b weft cops 50b of the second colour, the compartment 51c weft cops of the third colour, and the compartment 51d weft cops 50d of the fourth colour. In accordance with the weft cops 50a, 50b and 50d, four groups of shuttles are provided which are denoted 52a, 52b, 52c and 52d. All the shuttles conform with one another in having a contact plate 53 which is in electrically conductive connection with a second contact plate 54a in the shuttles 52a, 54b in the shuttles 52b, 54c in the shuttles 52c, and 54d in the shuttles 52d. The distance of the contact plate 54b from the contact plate 53 is twice, the distance of the contact

plate 54c from the contact plate 53 three times, and the distance of the contact plate 54d from the contact plate 53 four times as large as the distance of the contact plate 54a from the contact plate 53.

The feeler and selector device of the loom, by which the exchange of the cops is prepared, is represented merely diagrammatically in the drawing by 55. It can be constructed at will;

- 10 for example similar to what has been described with reference to Fig. 1. With 56 the slay of the loom is denoted on which there is actually a shuttle 52a, the weft cop 50a of which is exhausted and has to be exchanged. On the slay 56 a pusher member 57 is arranged which cooperates with a two-armed hammer lever 58 when a weft cop is to be exchanged. The hammer lever 58 is articulated by means of a pin 61 to one leg of a two-armed frog 59 which is 20 tiltably pivoted on a pin 60 stationarily arranged on the frame of the loom. On an axle 62, which is stationarily arranged on the frame of the loom, a two-armed control lever 63 is pivoted rotatably, one arm of which acts on one leg of the hammer lever 58, and the other arm of which is 25 acted upon by a relay 64. The relay 64 lies in a circuit R—T, which is controlled on the one hand by an interrupter 65, the rotary part of which is arranged on a shaft 66 revolving at the same R. P. M. as the crank shaft of the loom, and on the other hand by a feeler device 55. The relay 64 is provided with a holding contact 67 shunting the feeler device 55. As regards these components and the function thereof reference is made to the description of the first embodiment hereinabove.

In the shuttle-or exchange-box (not shown in the drawing) in which the exchange of the weft cop takes place, there are provided five, resilient 40 electrical contact pins 68, 69a to 69d, of which the contact pin 68 is connected to earth and cooperates with the contact plate 53 of all shuttles, whereas the contact pins 69a, 69b, 69c and 69d lie at such distances from the contact pin 68, that each of them can cooperate with the contact plates 54a, 54b, 54c and 54d, respectively, of the different groups of shuttles. The contact pins 69a, 69b, 69c and 69d are each in electrically conductive connection with one of the contact springs, 70a, 70b, 70c and 70d, respectively, of a switch, the stationary contact pieces of which are denoted 71a, 71b, 71c and 71d respectively. In the drawing only one of the contact springs and one of the stationary contact pieces are 55 visible, since they are arranged in a series behind one another. On an axle 72, which is stationarily arranged on the frame of the loom, for each contact spring 70a-70d a three-armed control lever 73a, 73b, 73c and 73d, respectively, is rotatably pivoted, one arm of which can act on the associated contact spring 70a, 70b, 70c and 70d, respectively. The second arm of these contact levers 73a, 73b, 73c and 73d carries a pin 74a, 74b, 74c and 74d, respectively, which lies in a slot 75a, 75b, 75c and 75d, respectively, at the end of a connecting rod 76a, 76b, 76c and 76d, respectively. The other ends of the connecting rods 76a, 76b, 76c and 76d are articulated each to an obturating flap 77a, 77b, 77c and 77d, respectively, which obturate the compartments 51a, 51b, 51c and 51d, respectively, of the cop magazine. The obturating flaps 77a, 77b, 77c and 77d are controlled by members of the selector and feeler device of the loom (not shown in the drawing) in such a manner, that after the ne-

cessity of the exchange of the weft cop of a shuttle has been ascertained by the feeler device, and the conformity of the respective shuttle with the group 52a, 52b, 52c and 52d, respectively, has been ascertained by the selector device, the obturator flaps 71a, 71b, 71c or 71d of that compartment 51a, 51b, 51c or 51d, respectively, which contains weft cops 50a, 50b, 50c or 50d, respectively, of the corresponding colour, is opened for a short time, in such a manner that a weft cop 50a, 50b, 50c or 50d can drop into the guide hopper 51' of the cop magazine 51 arranged below the compartments 51a, 51b, 51c and 51d. When the respective obturator flap 71a, 71b, 71c or 71d, is opened, the associated control lever 73a, 73b, 73c or 73d is rocked by the connecting rod 76a, 76b, 76c or 76d, respectively, which is articulated to it, in such a manner, that by one of its arms the associated contact spring 70a, 70b, 70c or 70d is brought into contact with the associated stationary contact piece 71a, 71b, 71c or 71d. The third arm of the control levers 73a, 73b, 73c and 73d is constructed as a stepped lever each of which cooperates with a two-armed locking pawl 78a, 78b, 78c or 78d, respectively, which are arranged behind one another on an axle which is stationarily arranged on the frame of the loom. One leg of these locking pawls 78a, 78b, 78c and 78d is connected to the stepped lever arm of the control lever 73a, 73b, 73c and 73d, respectively, by a tension spring 80a, 80b, 80c and 80d, respectively, which tends to bring the other leg of this locking pawl 78a, 78b, 78c and 78d, respectively, into engagement with the corresponding stepped lever arm. This has the consequence, that when by the temporary opening of one of the obturator flaps 71a, 71b, 71c or 71d one of the control levers 73a, 73b, 73c or 73d is turned, one leg of the respective locking pawl 78a, 78b, 78c or 78d engages into the stepped lever arm of this control lever 73a, 73b, 73c or 73d, and retains the same in this position deflected from the rest position. Owing to the slot 75a, 75b, 75c or 75d, respectively, of the corresponding connecting rod 76a, 76b, 76c or 76d, respectively, the obturator flap 71a, 71b, 71c or 71d concerned can nevertheless return at once into its closed position.

One leg of the locking pawls 78a, 78b, 78c or 78d is acted upon by one leg of a two armed release lever 81, which is pivoted on an axle 82 stationarily arranged on the frame of the loom. On the end of the other leg of the release lever 81 a pin 83 is arranged, which engages into an eye 84 of a connecting rod 85. At the upper end of this connecting rod 85 a second eye 86 is provided, in which lies a pin 87, which is arranged on a lever 88. The lever 88 is rotatably pivoted on an axle 89 on the guide hopper 51' of the cop magazine 51, and rigidly connected to it is a holder flap 90 arranged at the orifice of the guide hopper 51', which flap holds a weft cop 50a, 50b, 50c or 50d, which has dropped into the guide hopper, in a position of readiness for being pushed into the shuttle 52a, 52b, 52c or 52d.

The lower end of the connecting rod 85 is articulated to the end of one leg of a bell crank lever 91 which is rotatably pivoted on an axle 92 which is stationarily arranged on the frame of the loom. On the end of the other leg of this bell crank lever 91 a roller 93 is arranged, which runs on a cam disc 94. This cam disc 94 is arranged on a shaft 95 journalled in the frame of the loom which runs with half the R. P. M.

of the crank shaft of the loom. With the stationary contact pieces 71a, 71b, 71c and 71d a contact piece 96 is in electrically conductive connection, which is arranged on a carrier plate 97 of electrically insulating material provided on the guide hopper 51' of the cop magazine 51. On this carrier plate 97 there is moreover arranged an electrically conductive bracket 98 which carries an axle 99 on which a flap 100 is rotatably journalled opposite the orifice of the guide hopper 51'. This flap 100 is held by a spring 101 in such a position, that its portion lying above the axle 99 abuts against the carrier plate 97, and its portion lying below the axle 99 adjusts itself so that it carries together with the holder flap 90 a weft cop 50a, 50b, 50c or 50d which is in a position of readiness for being pushed-in.

On this flap 100 a two-armed feeler lever 102 is pivoted, which is in electrically conductive connection with the bracket 98. One leg of this feeler lever 102 is intended to test the position of the weft cop 50a, 50b, 50c or 50d which is in readiness for being pushed-in, and when the latter is in a correct position, it moves the said feeler lever 102 into such a position that its other leg comes into contact with the contact piece 96 and electrically connects the same to the bracket 98. The bracket 98 is connected to the conductor T between the source of current R-T and the interruptor 65.

When a shuttle 52a, 52b, 52c or 52d runs into the shuttle box on that side of the loom, on which the feeler and selector device 55 is arranged, it is ascertained by the feeler device 35 whether its weft cop has been exhausted and has to be exchanged. If this is the case, the feeler device closes the circuit of the relay 64 and, since at this moment the interruptor 65, too, 40 closes this circuit, the relay 64 responds, and the hammer lever 58 is brought through the control lever 63 into a position of readiness, i. e. into a position in which one of its legs lies in the path of the pusher member of the slay 56; 45 at the same time it has been ascertained by the selector device, whether the shuttle, that as arrived, belongs to the group 52a, 52b, 52c or 52d, and accordingly one of the obturator flaps 71a, 71b, 71c, or 71d is temporarily opened, so that, 50 in accordance with the weft cop tested in the shuttle, a weft cop 50a, 50b, 50c, or 50d drops into the guide hopper 51' of the cop magazine, and gets into a position of readiness for being pushed-in into the shuttle. Owing to the holding contact 67, the relay 64 remains in this position, 55 even when the shuttle leaves the shuttle box. In Fig. 2 the device is illustrated in the position immediately before the pushing-in of a new weft cop 50a, i. e. the feeler and selector device 55 has 60 already functioned, and the new weft cop 50a is in a position of readiness.

The pusher member 57 of the slay 56 is already in engagement with the hammer lever 58, and upon further movement of the slay 56, the 65 frog 59 comes into operation and pushes the new weft cop 50a, which is in a position of readiness in the guide hopper 51', into the shuttle 52a. By the previous temporary opening of the obturator flap 71a, before the shuttle 52a has left 70 the shuttle box on the side of the feeler and selector device, the control lever 73a has been turned by means of the connecting rod 76a, and this control lever 73a is now retained by the locking pawl 78a. Thereby the contact spring 75 70a is pressed against the stationary contact

piece 71a. By the weft cop 50a which is in a position of readiness, provided it is in the correct position, the feeler lever 102 is pushed into such a position, that it connects the bracket 98 in an electrically conductive way to the contact piece 96.

When now the shuttle 52a has entered the shuttle box on the exchange side, the contact pins 68a, 69a, 69b, 69c and 69d come into operation, i. e. they resiliently grip the incoming shuttle 52a. Since now the interruptor 65 interrupts the circuit at this moment, the following circuit is closed:

Conductor R—relay 64—earth—earthing contact pin 68—contact pin 69a—contact spring 70a—contact piece 71a—contact piece 96—feeler lever 102—bracket 98—conductor T.

The opened interruptor 65 is thereby shunted, and the relay 64 remains energized and holds the hammer lever 58 in a position of readiness. This circuit is not closed, when the selected new weft cop was taken from the correct compartment 51a of the cop magazine 51, i. e. when it is the case of a new weft cop 50a corresponding to the exhausted weft cop 50a of the shuttle 52a. If the weft cop were taken from another compartment of the cop magazine, one of the control levers 73b, 73c or 73d would have been turned by the opening of the obturator flap 77b, 77c or 77d, and thereby one of the contact springs 70b, 70c or 70d would have been pressed against the respective contact piece 71b, 71c or 71d. However, since the incoming shuttle belongs to the group 52a and comprised merely the contact plates 53 and 54a, closing of the circuit could not have been effected.

Likewise, the closing of the circuit does not take place when the incoming shuttle 52a with the cop 50a to be exchanged is not in the correct position in the shuttle box i. e. when it has not completely run-in, since in this case an electrical connection between the contact pins 68 and 69a over the contact plates 53 and 54a of the shuttle 52a would not have been established either. By an appropriate selection of the width of the contact plates 53, 54a, 54b and 54d as well as of the contact pins 68, 69a, 69b, 69c and 69d the range of the positions of the shuttle can be determined within which an exchange of the weft cop should take place.

Closing of the circuit referred to does not take place either, when no new weft cop is in a position of readiness or when this new weft cop lies obliquely or off-set in the guide hopper 51', since in this case the feeler lever 102 is not in contact with the contact piece 96.

When closing of the circuit referred to does not take place the relay 64 is disengaged, since its circuit is interrupted by the interruptor 65, and it drops off. Thereby the control lever 63 releases the hammer lever 58, and the latter turns under the action of its weight into a position in which its leg comes out of range of the pusher member 57 of the slay 56, so that operation of the frog 59 does not take place. This happens of course before the slay 56 has reached the position represented in the drawing.

When the new weft cop is pushed-in by means of the frog 59, the holder flap 90 is pushed back whereby the roller 93 is lifted off the cam disc 94, and the flap 100, too, is pressed back against the action of the spring 101. When a cop exchange initiated has been prevented owing to a wrong selection of the new weft cop 50a, 50b, 50c or 50d, to a wrong position of the shuttle 52a, 52b, 75

52c or 52d in the shuttle box, or to a wrong position of the new weft cop 50a, 50b, 50c or 50d in the guide hopper 51', the new weft cop 50a, 50b, 50c or 50d, which is in a position of readiness, has got to be removed from the guide hopper 51'. This is effected thereby that the holder flap 90 is temporarily moved back via the connecting rod 85 by the bell crank lever 91, the roller 93 of which runs on the cam 94, at every second pick 10 of the loom so that the weft cop, which is in a position of readiness, can drop out. The cam disc 94 is so constructed and adjusted, that this moving back of the holder flap 90 takes place immediately after the shuttle 52a, 52b, 52c or 52d, the weft cop 50a, 50b, 50c or 50d of which should have been exchanged, has left again the exchange box. Upon arrival of this shuttle 52a, 52b, 52c or 52d in the opposite shuttle box the holder flap has already been moved forward again.

The embodiment of the invention diagrammatically illustrated in Figs. 3 and 4 is intended for a loom which operates with weft cops of two different colours. On the frame of the loom (not shown in the drawing) a toothed rack 105 is shiftably guided. This toothed rack 105 is in its middle position during the normal operation of the loom, i. e. when no exchange of cops takes place, and it can be shifted to one side or to the other by the feeler and colour selector device 20 through an electric motor which can be reversed or through two electromagnets, according to whether a cop of one colour or of the other is to be exchanged. With 106a and 106b two shafts are denoted on each of which one of the obturator flaps (not shown in the drawing) of the two compartments of the cop magazine (likewise not shown in the drawing) is arranged. On the two shafts 106a and 106b a gear wheel 107a and 107b, respectively, is arranged idly rotatable, with which a second toothed rack 108 is in mesh. The gear wheel 107a is moreover in mesh with the toothed rack 105. On the shafts 106a and 106b a cam disc 109a and 109b, respectively, is fixedly keyed. These cam discs 109a and 109b carry at one side a dog 110a, 110b, respectively, which lie in recesses on the rim of the gear wheels 107a and 107b, respectively. When the toothed rack 105 is in the middle position, the dog 110a abuts on a limiting flank of the recess of the gear wheel 107b in such a manner that upon movement of 30 the toothed rack 105 in one direction the dog 110a is carried along by the gear wheel 107a whereby the cam disc 109a with the shaft 106a is turned whereas the dog 110b is not carried along because of the recess of the gear wheel 107b, and the shaft 106b is accordingly not turned, and conversely upon movement of the toothed rack 105 in the opposite direction the dog 110b is carried along by the gear wheel 107b, whereby the cam disc 109b with its shaft 106b is turned, while the shaft 106a is not turned. 40 The cam discs 109a and 109b have on their periphery a cam projection 109a' and 109b', respectively, which cooperates with a roller 111a and 111b, respectively, which is journaled at the end of one leg of a bell crank lever 112a, 112b, respectively. The bell crank levers 112a and 112b are rotatably pivoted on a common axle 113 which is stationarily arranged on the frame of the loom. To the end of the other legs of the two bell crank levers 112a and 112b one end of a connecting rod 114a, 114b, respectively, is articulated, the other end of which is articulated to one end of a two-armed stepped lever 115a, 115b, respectively. The stepped levers 115a and 115b are rotatably 50

journalled on a common axle 116 which is stationarily arranged on the frame of the loom. On the other ends of the stepped levers 115a and 115b a step 117a and 117b, respectively, is provided for one leg of a two-armed locking pawl 118a and 118b, respectively, which are rotatably journalled on a common axle 118' which is stationarily arranged on the frame of the loom. The stepped levers 115a and 115b are connected, to the associated locking pawl 118a, 118b, respectively, by a tension spring 119a, 119b, respectively, and a common abutment pin 120, stationarily arranged on the frame of the loom, delimits the angular deflection, which these locking pawls 118a and 118b can perform when the associated stepped lever 115a or 115b is rocked in such a manner that the leg of the locking pawl 118a, 118b, respectively, which lies below the step 117a, 117b, respectively, can move above this step 117a, 117b.

For each kind of weft cops, a control circuit is provided, the control of the weft cop being effected, if desired, in the same or a similar manner, as described and illustrated with reference to the embodiments described hereinabove. Only when one of these control circuits is closed, an exchange of cops can take place. In each of these control circuits an electrical switch is arranged, which consists in two switch pawls 121a, 121b, respectively, and 122a, 122b, respectively, which are tiltably pivoted on contact pieces 123a, 124a and 123b, 124b, respectively. The angular deflection of the switch pawls 121a and 121b is limited by an abutment pin 125. The switch pawls 122a and 122b are pressed by a spring 126a, 126b, respectively, against the associated stepped lever 115a, 115b, on which they abut by means of a roller 127a, 127b, respectively, journalled on them. With 128 the frog of the cop changing device of the loom is denoted, which is journalled on an axle 129. This frog 128 has a projection 130 to which a pin 131 is attached for the release of the locking pawls 118a and 118b. The connecting rods 114a and 114b, the stepped levers 115a and 115b, the locking pawls 118a and 118b, the tension springs 119a and 119b, the switch pawls 121a and 121b as well as 122a and 122b, the contact pieces 123a and 123b as well as 124a and 124b and their rollers 127a and 127b are arranged behind one another, so that they cover one another in the drawing.

In the drawing the control device is represented in that position which it assumes when no exchange of cops is to take place. The toothed rack 105 is in its middle position, and the cams 109a' and 109b' do not influence the rollers 111a and 111b of the bell crank levers 112a and 112b. The legs of the locking pawls 118a and 118b lie below the steps 117a and 117b of the stepped levers 115a and 115b, and the switch pawls 122a and 122b are lifted off the switch pawls 121a and 121b, so that consequently both control circuits are interrupted. When now an exchange of cops is initiated by the feeler and selector device of the loom, the toothed rack 105 is shifted by means of a reversible electric motor or of one of two electromagnets to one side or to the other, according to whether a cop of one kind or of the other is selected, and is immediately returned. When the toothed rack 105 is shifted, in the case represented e. g. downward, the gear wheel 107a carries the dog 110a along, and with it the cam disc 109a. Thereby the shaft 106a is rotated, and the obturator flap arranged on it opens temporarily its compartment of the cop magazine, so that a weft cop can drop out of this compartment

into a position of readiness, as described e. g. with reference to Fig. 2. The gear wheel 107b is also rotated by the toothed rack 108, but does not carry the dog 110b along, which then moves relative to it in the recess of the gear wheel 107b, so that accordingly the shaft 106b is not turned, and the obturator flap of the other compartment is not opened.

Upon rotation of the shaft 106a the cam 109a' acts on the roller 111a of the bell crank lever 112a and rocks the latter about its axle 113. Through the connecting rod 114a, the stepped lever 115a is rocked about its axle 116 in such a manner that the leg of locking pawl 118a emerges from the step 117a and is rocked upwards by the tension spring 119a, and abuts against the abutment pin 120. Thereby the end of this leg of the locking pawl 118a comes to bear against the stepped lever 115a above the step 117a and holds the same in this position, even when the cam 109a' of the cam disc 109a withdraws from the roller 111a when turning back.

By the rocking of the stepped lever 115a the switch pawl 122a has been pressed on to the switch pawl 121a against the action of the spring 126a, so that this switch is closed. When now by a feeler device, such as described e. g. with reference to the foregoing embodiments, the conformity of the weft cop of the shuttle arrived in the exchange box with the new weft cop brought into a position of readiness has been ascertained, and when by this feeler device the control circuit containing the switch pawls 121a and 122a has been closed, there is nothing to oppose the exchange of the exhausted weft cop; otherwise the control circuit remains interrupted with the consequence that the frog 128 can not be set into motion so that the exchange of the weft cop does not take place. When the exchange of a weft cop has been initiated by the feeler and selector device, the toothed rack 105 is shifted in the opposite direction, i. e. upwards, and is returned again. This has the effect that the gear wheel 107a is rotated without carrying along the dog 110a of the cam disc 109a while the gear wheel 107b carries the dog 110b along and turns the cam disc 109b with the shaft 106b, so that the obturator flap arranged on this shaft 106b temporarily opens its compartment of the cop magazine, and a weft cop of the other kind can drop into a position of readiness. At the same time the switch comprising the switch pawls 121b and 122b is closed in the manner described hereinabove.

In the pushing-in movement of the frog, the pin 131 arranged on its projection 130 abuts against the lower leg of the locking pawl 118a or 118b, which has rocked, and restores the locking pawl concerned to its initial position. Under the action of the tension spring 119a or 119b, the respective stepped lever 115a or 115b returns also into its initial position and allows also the switch pawl 122a or 122b to return again to their initial position, so that the control circuit concerned is again interrupted.

The control device according to Figs. 3 and 4 is suited particularly for looms, in which the movement of the frog is not derived from the movement of the slay but is generated in any other way.

When the condition is made that the cop exchange has to take place in one exactly defined position of the slay only, a further switch or interruptor can be provided in the control circuit which is closed mechanically or electrically in

one predetermined position of the slay only. For this purpose e. g. an interruptor having a rotating drum can be used, similar to the one described in the preceding embodiments.

When the further condition is made, that the exchange of cops should not take place, when immediately before that moment the weft thread has broken or has been exhausted, a further switch can be provided in the control circuit, which is from time to time opened or closed by the weft surveying device.

The control device according to Figs. 3 and 4 could be developed also for looms which operate with more than two different kinds of weft cops. For this purpose two or more toothed racks would have to serve two compartments of the cop magazine.

I wish it to be understood that I do not desire to be limited to the exact details of construction shown and described, for obvious modifications will occur to a person skilled in the art.

What I claim is:

1. A control device for the automatic exchange motion of the weft of looms, comprising in combination: an electric feeler and selector device for the weft cops, an interrupter operated by the said feeler and selector device, a preparatory circuit preparing the exchange of a weft cop interrupted by the said interrupter when the shuttle with the weft cop to be exchanged enters the shuttle box wherein the exchange of weft cops takes place, control circuits shunting the said preparatory circuit, switch members arranged in the said control circuits, holder members for the new weft cop prepared by the said preparatory circuit for being substituted for an old cop, the said holder means being controlled by the said control circuits, first control members ascertaining the conformity of the kind of the new weft cop with the old cop, second control members ascertaining the correct position of the shuttle in the shuttle box, and third control members ascertaining the correct position of the new weft cop for being exchanged, the said first, second and third control members operating the said switch members only when the said conformity of the cops correct position of the shuttle and correct position of the cop are established.

2. A control device for the automatic exchange motion of the weft of looms, comprising in combination: an electric feeler and selector device for the weft cops, an interrupter operated by the said feeler and selector device, a preparatory circuit preparing the exchange of a weft cop interrupted by the said interrupter when the shuttle with the weft cop to be exchanged enters the shuttle box wherein the exchange of weft cops takes place, control circuits shunting the said preparatory circuit, switch members arranged in the said control circuits, holder members for the new weft cop prepared by the said preparatory circuit for being substituted for an old cop, the said holder means being controlled by the said control circuits, different kind of shuttles for each kind of weft thread, two electrically connected contact plates on each shuttle arranged in different positions on the different kinds of shuttles, electrical contact pins arranged in the shuttle box wherein the exchange of cops takes place, one of the said contact pins being connected to one phase of the mains and each of the other contact pins being connected through one of the said control circuits to other phases of the mains, whereby the said control

circuits are closed according to the kind of shuttle in the correct position of the same only.

3. A control device as claimed in claim 2, comprising in addition: a switch member arranged in each of the said control circuits controlled by the new cop selected by the said selector device in the position of readiness for being substituted, and control means ascertaining the conformity of the new cop selected with the old one, the said control means allowing the closing of the said switch member only when the said conformity is established.

4. A control device as claimed in claim 2, comprising in addition: a rotatable cop magazine having two compartments for different kinds of weft cops, stationary abutments delimiting end positions for the said cop magazine, each end position corresponding to the discharge of one kind of cops from the said magazine, a cam member arranged on the said cop magazine, two switch members closed by the said cam member each of the said switch members being arranged in the control circuit corresponding to the kind of shuttles associated with the kind of weft cops to be discharged from the said magazine.

5. A control device for the automatic exchange motion of the weft of looms, comprising in combination: an electric feeler and selector device for the weft cops, an interrupter operated by the said feeler and selector device, a preparatory circuit preparing the exchange of a weft cop interrupted by the said interrupter when the shuttle with the weft cop to be exchanged enters the shuttle box wherein the exchange of weft cops takes place, control circuits shunting the said preparatory circuit, a cop magazine having different compartments for each kind of weft cops, flaps controlled by the said feeler and selector device, each flap controlling the discharge of cops from one of the compartments of the said cop magazine, spring biased stepped levers each operatively connected to one of the said flaps, spring biased locking pawls each associated with one of the said stepped levers, and electrical switches each associated with one of the said stepped levers and arranged in one of the said control circuits, each of the said flaps when temporarily opening its compartment of the said cop magazine turning its associated stepped lever into a position wherein it closes its associated switch, and the associated locking pawl dropping under its spring bias into the said stepped lever and locking the same in the deflected position.

6. A control device as claimed in claim 5, comprising in addition: a shaft rotated in operation at half the number of revolutions of the main crank shaft of the loom, a cam arranged on said shaft, a cam follower engaging said cam, a common holder member for weft cops discharged from any one of the compartments of the said cop magazine preparatory to being inserted into a shuttle operatively connected to the said cam follower, a common release lever for all the said locking pawls operatively connected to the said cam follower, the said cam automatically releasing the discharge of a cop from the said holder member by temporarily opening the said holder member and releasing the said stepped levers from being locked by the said locking pawls every second revolution of the main crankshaft of the loom.

7. A control device as claimed in claim 6 wherein the releasing action of the said cam is synchronised with the moment when the shuttle

leaves the shuttle box in which the exchange of the cops takes place.

8. A control device as claimed in claim 6 comprising in addition: a spring biassed feeler lever pivotally arranged opposite the said holder member in operative contact with the new weft cop, a common switch member controlling all of the said control circuits operated by the said feeler lever, the said feeler lever closing the said common switch member only when the new weft cop contacted by it is in the correct position preparatory to being inserted into a shuttle.

9. A control device for the automatic exchange motion of the weft of looms, comprising in combination: an electric feeler and selector device for the weft cop, an interrupter operated by the said feeler and selector device, a preparatory circuit preparing the exchange of a weft cop interrupted by the said interrupter when the shuttle with the weft cop to be exchanged enters the shuttle box wherein the exchange of weft cops takes place, control circuits shunting the said preparatory circuit, switch members arranged in the said control circuits, holder members for the new weft cop prepared by the said preparatory circuit for being substituted for an old cop, the said holder means being controlled by the said control circuits, a cop magazine having an even number of compartments each for a different kind of weft cops, a pair of flaps operated by the said feeler and selector device and controlling the discharge of cops from a pair of compartments of the said cop magazine, a pair of parallel shafts each shaft fixedly connected to one of the said flaps, a cam disc fixedly arranged on each of the said shafts, a dog attached to each cam disc, a gear pinion freely rotatable on each of said shafts having a recess engaging the said dog with angular play, a first toothed rack shiftably arranged on the loom controlled by the said feeler and selector device and having a middle position prior to the initiation of an exchange of cops and two end positions each corresponding to the initiation of the discharge of a cop from one compartment of the said cop magazine, the said toothed rack meshing with one of the said gear pinions, a second toothed rack meshing with both the said gear pinions and coupling the same for rotation, one dog being carried along by the flank of the recess of its associated gear pinion when the same is rotated in one direction by the shifting of the said first toothed rack and the other being left stationary by the said angular play in the recess of its associated gear pinion, the action being reversed upon shifting the said first toothed rack in the opposite direction, a pair of cam follower mechanisms each cooperating with one of the said cam discs, a pair of stepped levers each operatively connected with one of the said cam follower mechanisms, a pair of switch members each arranged in that one of the said control circuits which is associated with the kind of cops of the compartment of the cop magazine concerned controlled by the said stepped lever, and a pair of spring biassed locking pawls each locking one of the said stepped levers in its deflected position in which it closes its associated switch member.

10. A device as claimed in claim 9 comprising in addition: a frog, a release member arranged on the said frog in operative relation to the said locking pawls and releasing the said locking pawls from their position locking their associated stepped lever upon the said frog pushing a cop into a shuttle.

11. A control device for the automatic exchange motion of the weft of looms, comprising in combination: an electric feeler and selector device for the weft cops, an interrupter operated by the said feeler and selector device, a preparatory circuit preparing the exchange of a weft cop interrupted by the said interrupter when the shuttle with the weft cop to be exchanged enters the shuttle box wherein the exchange of weft cops takes place, control circuits shunting the said preparatory circuit, switch members arranged in the said control circuits, holder members for the new weft cop prepared by the said preparatory circuit for being substituted for an old cop, the said holder means being controlled by the said control circuits, first control members ascertaining the conformity of the kind of the new weft cop with the old cop, second control members ascertaining the correct position of the shuttle in the shuttle box, and third control members ascertaining the correct position of the new weft cop for being exchanged, the said first, second and third control members operating the said switch members only when the said conformity of the cops, correct position of the shuttle and correct position of the cop are established, and a switch arranged in each control circuit closed in dependence of the movement of the slay of the loom in a predetermined position of the said slay only.

12. A control device for the automatic exchange motion of the weft of looms, comprising in combination: an electric feeler and selector device for the weft cops, an interrupter operated by the said feeler and selector device, a preparatory circuit preparing the exchange of a weft cop interrupted by the said interrupter when the shuttle with the weft cop to be exchanged enters the shuttle box wherein the exchange of weft cops takes place, control circuits shunting the said preparatory circuit, switch members arranged in the said control circuits, holder members for the new weft cop prepared by the said preparatory circuit for being substituted for an old cop, the said holder means being controlled by the said control circuits, first control members ascertaining the conformity of the kind of the new weft cop with the old cop, second control members ascertaining the correct position of the shuttle in the shuttle box, and third control members ascertaining the correct position of the new weft cop for being exchanged, the said first, second and third control members operating the said switch members only when the said conformity of the cops correct position of the shuttle and correct position of the cop are established, a weft surveying device, and a switch arranged in each control circuit controlled by the said weft surveying device interrupting the said control circuits when the weft thread is broken or exhausted immediately prior to the exchange of a cop whereby this exchange does not take place.
